UNITED STATES PATENT OFFICE.

HORACE S. WILLIAMS, OF BROOKLYN, NEW YORK.

PAPER-CUTTING MACHINE.

Application filed December 5, 1922. Serial No. 605,069.

To all whom it may concern:

Be it known that I, HORACE S. WILLIAMS, a citizen of the United States, and a resident of the city of New York, borough of Brooklyn, in the county of Kings and State of New York, have invented new and useful Improvements in Paper-Cutting Machines, of which the following is a full, clear, and exact description.

10 The present invention relates to paper-cutting machines and it pertains more particularly to a new and improved method of attaching the cutting knives of such machines to the knife bar.

15 Great difficulty is experienced in removing and replacing the knives of paper-cutting machines for the reason that such knives are awkward to handle owing to their extreme weight and length.

20 It is one of the objects of the invention to construct the clamp of the machine so that it may be utilized to raise and lower the knife to position where it may be secured to or removed from the knife bar.

25 Paper-cutting machines as commonly constructed have a clamping element which serves to retain the stack of paper being cut in position upon the bed against shifting movement owing to the cutting action of the knife. This clamping member is moved vertically by means of a foot treadle and raised and lowered upon operation of such foot treadle.

30 With the above and other objects in view, reference is had to the accompanying drawings, in which—

Figure 1 is a detail front elevation of a paper-cutting machine showing the back guide and the knife bar;

40 Fig. 2 is a detail sectional view taken on the line 2—2 of Fig. 1;

Fig. 3 is a similar view showing one of the means for securing the knife to the knife bar removed and the knife attached to the clamp;

45 Fig. 4 shows the clamp in lowered position and removing the knife therefrom;

Fig. 5 is a view in elevation of one of the tools employed for removing the knife.

50 Fig. 6 is a detail plan view of the free end of the tool shown in Fig. 5, and

Fig. 7 is a detail perspective view of the means employed for securing the knife to the clamp.

55 Referring more particularly to the drawings, the reference character 10 designates

the knife bar, 11 the knife, 12 the means for securing the knife to the knife bar 10, 13 the vertically moving clamp, 14 the bed of the machine, and 15 the cutting strip.

60 In carrying out the present invention, the clamp 13 is provided with recesses 16, or the like, and said recesses are so positioned with respect to the clamp that when the knife bar 10 and the clamp 13 are in their uppermost position, the recesses 16 will be behind certain of the fastenings which secure the knife to the knife bar as shown in Fig. 2.

65 It has been found by actual experience that it is only necessary to provide the clamp 13 with two recesses 16, there being one adjacent each end of the clamp, but I do not wish to be limited to any specific number of recesses 16 since one or more may 70 be employed as desired.

75 In carrying out the invention the knife bar 10 and the clamp 13 are raised to their uppermost position, and as heretofore stated when these two elements are in this uppermost position, the recesses 16 in the clamp 13 are positioned behind their respective fastenings of the knife to the knife bar. With the parts in this position, the fastenings in front or opposite to the recesses 16 80 are removed and a suitable fastening is passed through the fastening opening of the knife bar into engagement with the knife and having its free end projecting into its respective recess in the clamp 13. Referring 85 to Fig. 7, it will be noted that the fastening element comprises a tubular member having an enlarged diameter 20 and a reduced diameter 21. The enlarged diameter 20 is a screw-threaded as shown at 22, and provided with 90 a kerf 23 for the engagement of a tool, by means of which the fastening may be rotated. The tool 30, as shown in Figs. 5 and 6, consists of a body portion or shank 30' having a curved end 31 to facilitate gripping of the tool. The opposite end of the tool is provided with a reduced portion 32, at the base of which is formed a flange 33, which flange is of a size to permit of its being introduced into the kerf 23 of the fastening heretofore mentioned.

95 After the fastenings which secure the knife 11 to the clamp 13 have been positioned, those fastenings which secure the knife to the knife bar 10 are removed, and when the 100 last-mentioned fastenings have been removed it is apparent that upon lowering 105

110 the clamp 13, the knife 11 will be held in the clamp 13 by the fastenings 12 which have been secured to the knife bar 10.

the clamp 13, the knife 11 will be carried downwardly therewith, it being understood, of course, that the tool 30 at each side of the machine is removed before the lowering operation of the clamp takes place. After the clamp has been lowered, the tools 30 are again inserted as shown in Fig. 4, and the knife 11 may be removed from the clamp 13 and completely removed from the machine.

While the foregoing describes the operation by which a knife is removed, it is obvious that if the clamp 13 is lowered and the knife attached by means of the special fastenings and the tool 30, when the clamp 13 is raised the knife will be moved to proper position relative to the knife bar 10 and the fastenings 12 heretofore mentioned may be positioned to secure said knife to the knife bar, after which the special fastenings are removed and the final arrangement of securing the knife to the knife bar is carried out.

From the foregoing it is apparent that the present invention provides means for positioning a knife and securing the same to the knife bar of a paper-cutting machine by employing the raising and lowering of the clamp of said machine, and that when such operation is carried out the knife bar 30 may be readily removed or replaced in the machine without danger on the part of the operator.

What is claimed is:

1. In a paper cutting machine, a knife, a knife bar to which the knife is adapted to be attached, a vertically movable clamp having recesses, means for securing the knife temporarily to said clamp to move the knife to position to be secured to the knife bar, and means for securing said knife to said knife bar.

2. In a paper cutting machine, a knife, a knife bar normally occupying an elevated position, a clamp having vertical movement and provided with a plurality of recesses, means for engagement with the recesses in the clamp for temporarily securing the knife

thereto to permit of it being elevated to the position of the knife bar, and means for securing the knife to the knife bar.

3. In a paper cutting machine, a knife, a knife bar, a clamp, a plurality of recesses formed therein, means adapted to pass through the knife and into engagement with the recesses in the clamp to temporarily secure the knife to the clamp, whereby the knife may be moved by the clamp to position adjacent the knife bar, and means for securing said knife to said knife bar.

4. The method of attaching knives to the knife bar of paper-cutting machines, which consists in temporarily securing the knife to the clamping bar of said machine, elevating the knife to the knife bar through the medium of the clamping bar, securing the knife to the knife bar, and removing the temporary fastening of the knife to the clamping bar.

5. In a paper-cutting machine, a reciprocating paper clamp, a reciprocating knife bar, a knife, said paper clamp and said knife having means to temporarily receive a fastener for attaching the knife to the clamp for raising the knife to the position of the knife bar, and means for securing the knife to the knife bar.

6. In a paper-cutting machine including a reciprocating paper clamp, a reciprocating knife bar, a knife, means independent of said knife bar to temporarily attach the knife to the clamp to cause the knife to be lifted to the knife bar in emplacing the knife, and means for securing the knife to the knife bar.

7. In a paper-cutting machine and in combination, a knife, a knife bar, means for securing said knife to the knife bar, and a clamp having a plurality of recesses therein, and means comprising a screw-threaded member having threaded engagement with the knife and extending into the recesses in the clamp to temporarily fasten the knife to the clamp.

HORACE S. WILLIAMS.
